UNITED STATES PATENT OFFICE.

FRANK A. MERRICK, OF JOHNSTOWN, PENNSYLVANIA, ASSIGNOR TO THE LORAIN STEEL COMPANY, OF PENNSYLVANIA.

TROLLEY.

SPECIFICATION forming part of Letters Patent No. 651,575, dated June 12, 1900.

Application filed September 14, 1899. Serial No. 730,437. (No model.)

To all whom it may concern:

Be it known that I, FRANK A. MERRICK, of Johnstown, in the county of Cambria and State of Pennsylvania, have invented a new and

5 useful Improvement in Trolleys, of which the following is a full, clear, and exact description, reference being had to the accompanying drawings, which form a part of this specification.

10 My invention relates to trolleys for electric cars which derive their current from an overhead conductor, and more particularly to the base or mounting by means of which the trolley arm or pole is connected to the roof of the car.

15 The objects of my invention are to provide a trolley-base which is of simple, durable, and inexpensive construction, which is sufficiently low to enable the car to which it is attached

20 to pass under low bridges or other overhead structures where there is but a limited space between them and the top of the car, and which is provided with novelly constructed and arranged spring means for maintaining

25 the required upward pressure of the trolley arm or pole, which are very effective in the character of their action.

With these objects in view my invention consists in the novel construction and combination of parts, all as hereinafter described, and pointed out in the appended claims.

30 Referring to the accompanying drawings, Figure 1 is a side view, partly in section, of my improved trolley base or mounting with the pole broken off; and Fig. 2 is a plan view of the same.

35 In the drawings the letter A designates a base-plate which is designed to be rigidly secured to the top of a car and which is provided with an upwardly-projecting pin or stud B, upon which is pivotally sleeved one end portion of an elongated arm C.

40 D designates the trolley arm or pole, to whose lower end portion is secured a socket-piece D', having an eye or barrel portion d, which seats between side flanges of the arm C and is pivoted to permit the usual swinging movement of the pole by means of a transverse pin E, which is seated in said side flanges. The piece D' has an upward and rear-

ward projection D², in which is seated a transverse pin f, having projecting end portions which are engaged by links G, whose lower ends support a second transverse pin H.

45 I is an elongated oblique bar or leaf spring which is seated between the side flanges of the arm C, one end being secured in a shoe J and its other or free end engaging the pin H. This spring is preferably composed of a number of superposed plates or laminæ of 55 different lengths, as shown. In order to provide means for adjusting its tension, the shoe J is pivoted in the arm C at the point J', and its opposite end portion loosely engages a threaded bolt or stud K, fixed in said arm, 60 and also seats a nut L, which engages the thread of said bolt or stud. It will be readily seen that by turning this nut the tension of the spring may be adjusted as may be required. Other suitable means may, however, 65 be provided for securing such adjustment. The action of the spring upon the trolley-pole to maintain upward pressure of the latter is obvious from the foregoing and from the drawings, Fig. 1 of which indicates different 70 positions of the spring as it is put under compression as the elevation of the trolley-pole is decreased, its action being practically *nil* when the pole is in its free or vertical position and gradually increasing as the pole approaches the horizontal. By tying together 75 the several plates or laminæ of the spring, as indicated at P, its action may be made effective in the opposite direction to prevent any tendency of the pole when free to pass 80 the vertical position. When the car is to be run in the opposite direction, the pole and arm C are swung around through an arc of one hundred and eighty degrees on the pin or stud B.

85 It will be readily seen that the base above described may be constructed so as to project but slightly above the roof of the car, the parts being few in number and compactly arranged. It will also be noted that the arrangement and character of the spring is extremely effective and that the life of the spring is much longer than that of the helical springs commonly employed in devices of this character, being free from bends and turns. An- 90 95 100

other advantageous feature of my improved base is that it presents above the car no parts which are liable to catch in low or broken overhead wires, all the parts with the exception of the pole being within the arm C.

5 I do not wish to be limited to the particular construction and arrangement which I have herein shown and described, as the same may be changed in detail without departing from the spirit and scope of my invention.

Having thus described my invention, what I claim, and desire to protect by Letters Patent, is—

1. The combination with a base-plate rigidly secured to the roof of a car, and an elongated horizontally-extending arm pivotally secured thereto, of a trolley-pole pivoted at its lower portion in the said arm, and having an upward rearward projection, an elongated flat or leaf spring secured at its rear end portion to the rear end portion of the said arm, and a loose connection between the opposite end portion of the said spring and the projection on the pole, substantially as described.

25 2. The combination with a base member rigidly secured to the roof of a car, and an elongated horizontal arm pivotally secured to said member, of a trolley-pole pivoted to said arm near the pivotal point of the latter, a flat spring secured at one end to the opposite end portion of the said arm, and a link connecting the opposite end portion of said spring to the pole, substantially as described.

3. The combination with a base-plate, and an elongated horizontal arm pivotally secured thereto, of a trolley-pole pivoted to the said arm, and having an upward rearward projection at its lower end, a pair of depending links secured to the said projection, a pin carried 40 by the said links, a flat spring secured at one

end to the said arm, and at the other end to the said links.

4. In a trolley, the combination of a base-piece, an elongated arm pivoted thereto and having side flanges, a trolley-pole having its 45 lower end portion pivotally secured between the said flanges, a flat spring fixed at one end in the outer portion of the said arm, and links connecting the other end portion of said spring to the trolley-pole.

5. In a trolley, the combination of a base-piece, an elongated arm pivotally secured thereto and having side flanges, a trolley-pole having its lower end portion pivotally secured between the said flanges, an elongated flat 55 spring inclosed by said flanges and fixed at one end to the said arm, and links connecting the opposite end portion of the spring with the trolley-pole.

6. In a trolley, the combination of a horizontally-movable arm, a trolley-pole pivoted thereto, a flat spring connected at one end to the said pole, a pivoted shoe in which the opposite end portion of said spring is seated, and means for adjusting said shoe on its 60 pivot.

7. The combination with the pivoted trolley arm or pole, and the flat spring connected thereto, at one end, a pivoted shoe in which said spring is seated at its opposite end, a threaded bolt or stud and an adjusting-nut carried by the said shoe and engaging said bolt or stud.

In testimony whereof I have affixed my signature in presence of two witnesses.

FRANK A. MERRICK.
